COMBINATION LOCK FOR BICYCLES OR THE LIKE

Hisashi Saito, Nagoya, Japan, assignor to Kabushiki
Kaisha Saikosha Seikakusho, Kasugai, Aichi Prefecture,
Japan

Filed Feb. 5, 1970, Ser. No. 21,287

Term of patent 14 years

Int. Cl. D8—03
U.S. Cl. D8—114

FIG. 1

FIG. 2

FIG. 4

FIG. 3

FIG. 5

FIG. 6

FIG. 1 is a front view of a combination lock for bicycles or the like, showing my new design;

FIG. 2 is a top plan view thereof;

FIG. 3 is a bottom plan view thereof;

FIG. 4 is a right end view of FIG. 1;

FIG. 5 is a perspective view thereof; and

FIG. 6 is a perspective view of the lock showing the plug member thereof disengaged from the body member of the lock.

I claim:

The ornamental design for a combination lock for bicycles or the like, as shown.
